UNITED STATES PATENT OFFICE.

HARRY P. PRATT, OF CHICAGO, ILLINOIS.

ELECTRODE FOR THERAPEUTIC BODY-WEAR.

SPECIFICATION forming part of Letters Patent No. 406,306, dated July 2, 1889.

Application filed March 12, 1889. Serial No. 302,960. (No model.)

To all whom it may concern:

Be it known that I, HARRY P. PRATT, a citizen of the United States, residing at Chicago, in the county of Cook and State of Illinois, 5 have invented a new and useful Improvement in Electrodes for Electro-Therapeutic Body Appliances, of which the following is a specification.

Of the electrodes hitherto employed in connection with electric belts, trusses, and the like electro-therapeutic body appliances those most commonly used have been formed of stiff metal, which is not, obviously, adapted to absorb moisture. The inflexible electrode, 10 when used in the connection referred to, is objectionable, for the reason that it does not possess the capability of conforming to the surface of the body to which it is applied in all conditions and positions of the body, therefore 15 by to follow the surface in all shapes or conditions it may assume by movement of the body. Owing to this lack it happens frequently that but a portion, sometimes a very small portion, of the surface of an electrode 20 will be in contact with the surface of the body to which it is applied, and thus cause the entire current to pass through a comparatively small portion of the electrode, thereby increasing the resistance where it enters the 25 body and tending to burn and even blister the surface subjected to the current.

The object of my improvement is to provide a form of electrode which may involve, without inconvenience to the user, a comparatively large extent of surface, and which shall be flexible to conform readily to the surface of the body to which it may be applied, and which shall, further, be formed with material absorbent of moisture to enable 30 it to be moistened when applied to the body, thereby to increase the conductivity.

One of the purposes for which I particularly design my improved electrode is to afford a cushion to be interposed between the 35 pad of an electric truss and the part of the body to which the pad is applied, and I illustrate my improvement in connection with an electric truss in the accompanying drawings, in which—

50 Figure 1 is a truss having upon it a suita-

ble electric battery with which are connected electrodes of my improved construction; and Fig. 2 shows the electrode in its preferred form in elevation with one of the two outer layers of the chamois-skin, with which I prefer to form it, removed to display the construction of the metallic element I prefer to employ and which is fastened between the layers.

A is the electrode, which I prefer to form 60 as shown most clearly in Fig. 1—namely, of two rounded layers r and r' , of flexible absorbent material, (chamois-skin being the most desirable material, or one, the layer r , of chamois-skin, and the other r' of soft leather,) 65 sewed or otherwise fastened together and having secured between them a continuous strip of fine woven wire p , silver wire being preferred. A conductor q is fastened to one end of the woven wire p , and extends therefrom out of an 70 opening o between the layers, being provided at its opposite end with means, such as the clamp n , (though any suitable means for or manner of producing the connection will answer my purpose,) for connecting it to an electric battery B, which may, and preferably does, comprise the construction set forth in Letters Patent of the United States No. 388,581, granted me on the 28th day of August, 1888, for improvement in electric belts. 75

The battery B is applied to the girdle portion of a truss C, as shown, and in the same manner as it is applied to the analogous part of an electric belt; but for a truss the electrode A, to be interposed between the truss-pad m and rupture to which it is applied, should involve the form illustrated, while the other electrode, which I distinguish as A', may be formed to surround the girdle portion of the truss, as shown, but should otherwise 90 be constructed like the electrode illustrated in Fig. 2, and it is similarly provided with means for connecting it with the opposite pole of the battery B. When used on an electric belt, however, the electrode A may comprise 95 the form of and be applied like that (the electrode A') shown as embracing the girdle portion.

The rounded electrode A should present a surface somewhat larger than that of the pad 100

m, and to use it, the truss, with both electrodes connected with the poles of the battery *B*, is adjusted on the body of the wearer in the usual manner, and the sides of the electrodes 5 to come into contact with the body are moistened, preferably by saturating them with water. The adjustment of the truss brings the electrode *A'* on the girdle portion into contact with the body, when it may, if necessary, 10 be shifted to any desired position, as will readily be understood from inspection of Fig. 1. The rounded electrode *A*, however, is most conveniently applied after the truss has been adjusted, by interposing it between the truss- 15 pad *m* and rupture.

From the foregoing description it will be readily apparent that the objects hereinbefore stated to be accomplished by my improvement are attained, since the construction of 20 the electrode presents a soft and therefore comfortable texture to the skin, is pliable, whereby its entire extent of surface applied to the body remains in contact therewith, and by being saturated with moisture, whereby it 25 also moistens the surface of the skin, increases its conductivity, the construction thus also preventing injury from the effects of the current—such as burning or blistering—to the surface of the body to which it is applied.

30 What I claim as new, and desire to secure by Letters Patent, is—

1. An electrode for use with electro-therapeutic body appliances and formed with flexible absorbent material, having a flexible metallic conductor *p* secured to it, substantially 35 as and for the purpose set forth.

2. In an electrode for use with electro-therapeutic body appliances, the combination of a

layer *r*, of flexible absorbent material, a layer *r'*, of flexible material, secured to the layer *r*, 40 an interposed flexible metallic conductor *p*, and a conductor *q*, attached at one end to the conductor *p* and provided at its opposite end with means for connecting it with an electric generator, substantially as and for the pur- 45 pose set forth.

3. In combination, a truss *C*, an electric battery *B* upon the truss, and electrodes connected with the opposite poles of the battery, and each formed with flexible absorbent ma- 50 terial having a flexible metallic conductor *p* secured to it and from which connection of the electrode with the battery is made, sub- substantially as and for the purpose set forth.

4. In combination, a truss *C*, an electric bat- 55 tery *B* upon the truss, an electrode *A'* upon the girdle portion of the truss and comprising a layer *r*, of flexible absorbent material, a layer *r'*, of flexible material, the said layers being secured together, and a flexible metal- 60 lic conductor *p*, interposed between the layers and from which connection of the electrode with the battery is made, and an electrode *A*, to be interposed and form a cushion between the pad of the truss and surface of the body, 65 and comprising a layer *r*, of flexible absorbent material, a layer *r'*, of flexible material, the said layers being secured together, and a flex- 70 ible conductor *p*, interposed between the layers and from which connection of the electrode with the battery is made, substantially as and for the purpose set forth.

HARRY P. PRATT.
